(57) **CLAIM**

The ornamental design for a license plate frame, as shown and described.

DESCRIPTION

FIG. 1 is a perspective front view showing our new design for a license plate frame.

FIG. 2 is a magnified view of a portion of the license plate frame shown in FIG. 1.

FIG. 3 is a front view of the license plate frame of the present invention.

FIG. 4 is a back view of the license plate frame of the present invention.

FIG. 5 is a right side view of the license plate frame of the present invention, the left side view being the mirror image thereof.

FIG. 6 is a top view of the license plate frame of the present invention, the bottom view being the mirror image thereof.

FIG. 7 is a perspective front view showing a second embodiment of our design for a license plate frame, with a second bow added to the design shown in FIG. 1.

FIG. 8 is front view of the license plate frame shown in FIG. 7.

FIG. 9 is a right side view of the license plate frame shown in FIG. 7, the left side view being the mirror image thereof.

FIG. 10 is a top view of the license plate frame shown in FIG. 7, the bottom view being the mirror image thereof.

FIG. 11 is a front perspective view showing a third embodiment of our design for a license plate frame, with the second bow moved to a different corner of the frame from the design shown in FIG. 7.

FIG. 12 is a front view of the license plate frame shown in FIG. 11.

FIG. 13 is a front perspective view showing a fourth embodiment of our design for a license plate frame, with the second bow moved to a different corner of the frame from the designs shown in FIG. 7 and FIG. 11.

FIG. 14 is a front view of the license plate frame shown in FIG. 13.

FIG. 15 is a front perspective view showing a fifth embodiment of our design for a license plate frame, with the single bow moved to a different corner of the frame from the design shown in FIG. 1; and,

FIG. 16 is a front view of the license plate frame shown in FIG. 15.
